UNITED STATES PATENT OFFICE.

MARIE ANNINA PHILLIPS, OF NEW YORK, N. Y.

HAT.

1,300,644.

Specification of Letters Patent. Patented Apr. 15, 1919.

Application filed October 3, 1918. Serial No. 256,695.

To all whom it may concern:

Be it known that I, MARIE A. PHILLIPS, a citizen of the United States, residing at New York, in the county of New York and 5 State of New York, have invented certain new and useful Improvements in Hats; and I hereby declare that the following is a full, clear, and exact description thereof, reference being had to the accompanying 10 drawings, which form part of this specification.

This invention is a novel hat especially adapted for ladies' wear; to be made of any suitable material; and which is simple in 15 construction, very comfortable, neat and attractive in appearance and serviceable. It also has the advantages of being readily adjusted in a variety of different shapes or styles at the will of the wearer; and it can 20 be packed flat in a valise or trunk without injury.

I will explain the construction of such hat with reference to the accompanying drawings, and set forth in the claims the 25 novel construction and features thereof for which protection is desired.

In said drawings:

Figure 1 is a front view of the hat showing it adjusted to simplest form.

Fig. 2 is a sectional view thereof on line 2—2, Fig. 1.

Fig. 3 is a view of blank for the crown of the hat.

Fig. 4 is a view of the blank for the rim 35 of the hat.

Fig. 5 is a front view of the blank for the crown folded.

Figs. 6, 7 and 8 are detail views showing 40 different arrangements in which the hat can be adjusted for wear.

The crown and brim portions of the hat may be of any desired material and color.

The crown 1 is preferably formed out of a square piece of material, shown flat in Fig. 45 3. This piece of material is plaited at each corner along the dottel lines 1^a 1^b indicated in Fig. 3. The lines 1^b indicating the inner edges of the plaits, and the lines 1^a the outer edges of the plaits; and when thus 50 plaited the crown is shaped and formed with front and rear box plaits 1^c and 1^d on the crown, and outwardly folded side plaits at opposite sides of the box plaits as indicated in Figs. 2 and 5. After plaiting the crown 55 the points or corners 1^e of the blank, which would project beyond the base of the crown,

are cut off on approximately the line indicated at 1^h in Fig. 5.

The brim 2 is made out of suitable soft material preferably doubled upon itself, as 60 shown, so that the brim will be finished on both sides. The brim is preferably greater in depth or width than the height of the crown, and its lower or inner edge is attached to the lower edge of the crown and 65 corresponds in diameter therewith; while its outer or upper edge is slightly larger in diameter than its inner edge as indicated in Figs. 1 and 2 so that the brim will normally tend to stand substantially upright as in 70 said figures, when the hat is worn. The brim is soft and is gathered on each side near its lower edge as indicated at 2^a so that the inner or lower edge of the brim will approximately conform in extent to the lower 75 edge of the crown, and the inner edge of the brim is preferably turned under the edge of the crown as shown in Fig. 2 and sewed thereto. The front and rear portions of the brim opposite the box plaits 1^c, 1^d of the 80 crown are left plain as at 2^b while the gathered portions 2^a appear at each side of the hat.

The brim 2 may be made of a straight piece of goods folded to the proper width 85 and cut to the proper length and its ends united as indicated in Fig. 4. This brim blank is then gathered adjacent one edge along the lines 2^c, 2^d, 2^e indicated in Fig. 4. Preferably three rows of gathers are made. 90 After the gathers are put in the brim is attached to the crown on the line indicated at 2^e, and the lower row of gathers below the line 2^c (Fig. 4) are turned within the crown.

The selvage 2^s may be sewed to the crown 95 after it is turned under and before the lining is attached. A lining 3, of any suitable material, is sewed to the inner side of the brim within the crown along this line.

The crown and brim and the lining can 100 all be cut on the straight of the goods.

As an example, to make such a hat out of velvet would require 1 yard and 20 inches of velvet 18 inches wide; and 7 $\frac{1}{4}$ inches of taffeta lining 27 inches wide, which is cut 105 off according to size of hat, as it is used on the straight.

The crown 1 requires $\frac{1}{2}$ yard of velvet (18 inches wide) which makes a square as per pattern Fig. 3, and is plaited as above explained and the corners then cut off making 110 a round crown when finished.

The outer ruffle or brim 2 requires 1 yard and 2 inches of velvet, which is the length, and which is sewed together after having been doubled to a width of $7\frac{1}{4}$ inches to sel-
5 vage and made according to pattern, Fig. 4.

The lining 3 requires $7\frac{1}{4}$ inches of taffeta (as stated above) which is turned under each side to a width of $6\frac{1}{2}$ inches and sewed in hat according to pattern of hat and is
10 gathered at crown according to size of head.

In the simplest adjustment of the hat shown in Fig. 1 the brim stands up straight but full all around the crown; and Figs. 6, 7 and 8 show some of the different styles or
15 shapes in which the hat can be readily adjusted by the wearer; each of them being attractive in appearance; thus enabling the hat to be adjusted to best correspond with the dress of the wearer.

20 The hat is made without any stiffening, but the Shirred portion and general configuration of the brim the construction of the crown and the connection of the brim to the crown gives the hat a substantial degree of
25 stiffness around the part corresponding to the band, and insures that the brim and crown will retain the shapes to which they are adjusted when worn.

As the hat does not require any stiffening
30 in the crown or brim it can be folded flat, when not in use, and be packed flat in a valise or trunk for transportation, and it can be folded compactly without injury.

The double thickness of the brim and its
35 form enhances its stiffness when worn and enables the brim to be displayed either side out at the will of the wearer; and to be adjusted in any shape or style desired and retain same while worn.

40 What I claim is:

1. A collapsible adjustable hat for ladies' wear comprising a crown portion and a brim portion having its inner edge connected to the lower edge of the crown and conforming in diameter therewith, and having its outer edge slightly larger in diameter than its inner edge so that the rim will normally stand up when the hat is worn; the brim and
45

crown being made of soft material so that the upper part of the brim may be readily adjustable to different positions and retain the same when the hat is worn; and the hat can be folded flat when not in use.

2. An adjustable hat for ladies' wear comprising a crown portion formed out of suitable soft material and a brim portion also formed of soft material and having its inner edge connected to the lower edge of the crown and conforming in diameter therewith, and having its outer edge slightly larger in diameter than its inner edge so that the rim will normally stand up when the hat is worn; the brim being Shirred on opposite sides adjacent the lower edge thereof to contract such edge to approximately the circumference of the lower part of the crown; the lower edge of the Shirred portion of the brim being sewed to the lower edge of the crown portion; the brim being readily adjustable to different positions and retaining such positions when the hat is worn, substantially as described.

3. A lady's hat composed of a crown portion of soft material having front and rear box plaits; and a brim of soft material folded upon itself, and Shirred or gathered near its lower edge on opposite sides to reduce the circumference of such lower edge to the approximate circumference of the lower edge of the finished crown portion, the upper edge of the brim being slightly larger in diameter than its lower edge so that the brim will normally stand up when the hat is worn; the lower portion of the Shirred edge of the brim being turned under the lower edge of the crown and sewed thereto, the portions of the brim adjacent the box plaits on the crown being left unshirred; the brim and crown being made of soft material so that the brim may be readily adjustable to different positions when the hat is worn; and the hat can be folded flat when not in use.

In testimony that I claim the foregoing as my own, I affix my signature.

MARIE ANNINA PHILLIPS.
